US00D788082S

(12) **United States Design Patent** (10) Patent No.: **US D788,082 S**
(45) Date of Patent: **** May 30, 2017**

(54) **ANTENNA**

(71) Applicant: **Airgain, Incorporated**, San Diego, CA
(US)

(72) Inventors: **Bei Zheng**, Zhang Jia Gang (CN);
Mengyi Tao, Zhang Jia Gang (CN);
Ziming He, Irvine, CA (US)

(73) Assignee: **Airgain Incorporated**, San Diego, CA
(US)

(**) Term: **15 Years**

(21) Appl. No.: **29/540,023**

(22) Filed: **Sep. 20, 2015**

(51) LOC (10) Cl. **14-03**

(52) U.S. Cl.

USPC **D14/230**

(57) **CLAIM**

The ornamental design for an antenna, as shown and described.

DESCRIPTION

FIG. 1 is a top plan view of an antenna with a base in broken lines;

FIG. 2 is a side elevation view thereof;

FIG. 3 is a front elevation view thereof;

FIG. 4 is bottom plan view thereof;

FIG. 5 is a top perspective view thereof;

FIG. 6 is a top plan view of the antenna without the unclaimed base structure; and,

FIG. 7 is a front elevation view thereof.

The broken lines are for illustrative purposes only and form no part of the claimed design.

1 Claim, 5 Drawing Sheets
